UNITED STATES PATENT OFFICE.

FRANK L. LEDFORD, OF CORDELE, GEORGIA.

QUILTING-FRAME.

1,175,778.

Specification of Letters Patent. Patented Mar. 14, 1916.

Application filed May 8, 1915. Serial No. 26,814.

To all whom it may concern:

Be it known that I, FRANK L. LEDFORD, a citizen of the United States, residing at Cordele, in the county of Crisp and State 5 of Georgia, have invented new and useful Improvements in Quilting-Frames, of which the following is a specification.

The invention relates to quilting frames, and has for its primary object to provide 10 a frame of this character wherein the work will be held during the quilting operation relative to a sewing machine so that the work can be handled with despatch, and the required design stitched with the greatest 15 ease.

Another object of the invention is the provision of a frame of this character which can be readily applied to any sewing machine without marring or disfiguring the 20 top thereof, as the work will be suspended so that it can be conveniently handled irrespective of the size thereof, and also will obviate the overbalancing of the sewing machine when in operation.

25 A further object of the invention is the provision of a quilting frame of this character wherein the construction thereof is novel in form to assure the perfect working of the same.

30 A still further object of the invention is the provision of a quilting frame of this character which is simple in construction, readily and easily adjusted, reliable and efficient in operation, strong, durable, and inexpensive in manufacture.

35 With these and other objects in view, the invention consists in the construction, combination and arrangement of parts as will be hereinafter fully described, illustrated in 40 the accompanying drawings, and pointed out in the claims hereunto appended.

In the drawings:—Figure 1 is an elevation of a quilting frame constructed in accordance with the invention. Fig. 2 is a top 45 plan view thereof. Fig. 3 is a sectional view on the line 3—3 of Fig. 1. Fig. 4 is an end elevation. Fig. 5 is a fragmentary longitudinal sectional view through one of the fabric supporting rolls showing the 50 manner of locking the same against rotation. Fig. 6 is a perspective view of the quilting frame and its support.

Similar reference characters indicate corresponding parts throughout the several 55 views in the drawings.

Referring to the drawings in detail, A designates generally the hanger frame, and B the movable quilting frame, both being hereinafter fully described.

The hanger frame comprises a pair of 60 spaced vertical standards or uprights 5 supported by the cross base members forming the feet 6 therefor, while fixed to the upper ends of the supports or uprights is a sectional cross rail 7, the sections of which being 65 suitably adjustably connected to each other so that the size of the frame may be varied as the occasion may require. Connected to the uprights 5 below the rail 7 is a cable 8 from which is suspended the quilting frame B hereinafter described.

The quilting frame B comprises the channeled end rails 9, between which are arranged the respective fabric supporting rolls 10 and 11, each having the disk ends 12, and 75 the axles or journals 13 of these rolls are journaled in the rails 9 near opposite ends thereof, the said rails being formed with slots 14 opening through one end of each so that the roll 11 can be detached therefrom 80 for the removal of the quilt from the frame B when it has been finished.

Fixed in the channels of the rails 9 are resilient catches 15 which are adapted to engage in any one of the holes 16 formed in 85 the disk ends 12 of the rolls 10 and 11 so as to lock the said rolls against rotation, while engaged in the end rails 9 are rings 17 to which are loosely connected suspension rods 18, the same being engaged with coupling 90 members 19 to which are loosely connected hangers 20 having connected thereto chains 21, the same being adapted for adjustable engagement with hooks 22 mounted in and depending from a carriage which is in the 95 form of a beam 23 having fitted therein pulleys 24 which engage and travel upon the cable 8 so that the quilting frame B can be moved at will.

Connected to a pair of the rings 17 which 100 are disposed at opposite ends of the quilting frame B are bracing cords 25 having loop ends 26 for detachable engagement with the hooks 22, and these cords serve to prevent the swaying or the lateral rocking 105 movement of the quilting frame when suspended for use.

Mounted longitudinally on the rolls 10 and 11 are strips 27 to which are detachably connected the ends of the fabric to be quilt- 110

ed, so that on the turning of the rolls the said fabric will be unwound from one of the same and wound upon the other during the quilting operation by the use of a sewing machine as usual.

From the foregoing description, taken in connection with the accompanying drawing, the construction and operation of the device will be clearly understood, and therefore a more extended explanation has been omitted.

What is claimed is:—

1. A quilting frame comprising spaced channeled end rails, rolls journaled in the said end rails and having disk-like ends provided with holes near the peripheries thereof, resilient catches mounted in the channels of the end rails and engageable in the holes of the respective end disks of the rolls, a support, means for suspending the said end rails and permitting the movement thereof relative to the support, and connections between the end rails and the suspen-

sion means to prevent the rocking of the quilting frame.

2. A quilting frame comprising spaced channeled end rails, rolls journaled in the said end rails and having disk-like ends provided with holes near the peripheries thereof, resilient catches mounted in the channels of the end rails and engageable in the holes of the respective end disks of the rolls, a support, means for suspending the said end rails and permitting the movement thereof relative to the support, connections between the end rails and the suspension means to prevent the rocking of the quilting frame, and means for vertically adjusting the quilting frame.

In testimony whereof I affix my signature in presence of two witnesses.

FRANK L. LEDFORD.
